DESIGN FOR A RECEPTACLE OPENER

Herman Erxleben, Rensselaer, N. Y.

Application July 13, 1940, Serial No. 93,617

Term of patent 3½ years

To all whom it may concern:

Be it known that I, Herman Erxleben, a citizen of the United States, residing at Rensselaer, in the county of Rensselaer and State of New York, have invented a new, original, and ornamental Design for a Receptacle Opener, of which the following is a specification, reference being had to the accompanying drawing, forming part thereof.

I claim:

The ornamental design for a receptacle opener, as shown.

HERMAN ERXLEBEN.
